UNITED STATES PATENT OFFICE.

JOHN BOSTON, OF NEWARK, NEW JERSEY, ASSIGNOR, BY MESNE ASSIGNMENTS, TO
T. HARDEN CARTER.

AUTOMATIC STOP MECHANISM FOR SEWING MACHINES.

Original application filed September 4, 1918, Serial No. 252,527. Patent No. 1,502,544, dated July 22, 1924. Divided and this application filed September 18, 1923. Serial No. 663,489.

This invention relates to improvements in sewing machines and more particularly to a stop mechanism specially applicable to automatic hemstitching machines and the like such as are used for hemstitching the side edges of long strips of fabric which are subsequently cut into short lengths and hemstitched across the ends to form handkerchiefs. I will hereinafter describe my invention as applied to such machines, but without intending to limit it to such application.

The present invention constitutes a division of application, Ser. No. 252,527, upon which Letters Patent No. 1,502,544, issued to me on July 22, 1924.

One of the objects of my invention is to provide an improved mechanism particularly applicable to automatic sewing machines of the above character which will contribute to their automatic operation whereby a single operator without special training may attend a plurality of machines.

A further object is to provide reliable and efficient means adapted to be applied to sewing machines of the above character for automatically controlling the starting and stopping of the machine. The device, which is of simple and practical construction, is adapted to be positioned within easy reach of the operator from all positions around the machine, and in the preferred embodiment of the invention the automatic stopping device hereinafter described is associated or combined with a main operating lever in order that the latter will set the automatic device in condition for automatic operation.

A further object is to provide an automatic mechanism of the above character adapted to stop the machine on exhaustion of the supply of fabric whereby the machine will cease its stitch operation. This device in no way interferes with the operation of the stitching mechanism and is so constructed as to operate in conjunction with the sewing machine proper.

Another object of my invention is to provide a mechanism for carrying out the above which may be attached to the standard sewing machines now on the market without

material modification thereof and without interfering with their operation and which mechanism shall be simple to manufacture and operate.

Other objects will be in part obvious from the annexed drawings and in part indicated in connection therewith by the following analysis of the invention.

This invention accordingly consists in the features of construction, combination of parts and in the unique relations of the members and in the relative proportioning and dispositioning thereof, all as more clearly outlined herein.

To enable others skilled in the art so fully to comprehend the underlying features thereof that they may embody the same by numerous modifications in structure and relation contemplated by this invention, drawings depicting a preferred form have been annexed as a part of this disclosure, and, in such drawings, like characters of reference denote corresponding parts throughout all the views, of which:

Figure 1 is a front elevation of a sewing machine with my improvement applied thereto, the gate being omitted;

Figure 2 is a partial rear elevational view of the upper part of the machine;

Figure 3 is a partial plan view with the gate omitted;

Figure 4 is a side elevational view partly in section showing the lower part of the machine; and

Figure 5 is a sectional view taken near the right hand end of the head of the machine.

Referring now to the drawings in detail and more particularly to Figure 1, there is illustrated a sewing machine head 1, of any desired type preferably suitable for hemstitching. This head is mounted upon an elongated bench 2 adapted to support a plurality of similar machines in a row or rows if desired, whereby they all may be driven from a single main source of power. The frame 3 of the machine is provided with a needle shaft 4 carrying a needle 5, a tension device 6 and a take-up arm 7, a needle oscillator link 8, a balance wheel 9, a drive pulley 10 and a spool holder 11, all of the

usual well-known type and cooperating one with another as is familiar to those skilled in the art. The needle thread 12 leads from the spool through to a guide 13 and tension device 6 thence over a pin 14 and arm 15 carried by a part of the take-up thence to the needle.

The sewing machine proper is adapted to be operated from the main shaft 16 by means of a belt 17 traveling over a pulley 18 to the pulley 10 on the sewing machine. A worm 19 on the main shaft 6 operates through a worm 20 to turn a shaft 21 which latter operates through bevel gears 22 to rotate a counter shaft 23 at a reduced rate of speed. A belt 24 passes over a pulley on the counter-shaft 23 thence to a pulley 25 on a short shaft 26 by means of which the shaft 26 is operated from the counter-shaft 23 as will appear more clearly by reference to Figure 4.

The strip of fabric to be stitched is fed into the machine over what is known as a gate 27, as shown more clearly in Figure 4 and fully illustrated and described in my prior patent, No. 1,391,876, and this gate forms no part of the present invention specifically except in so far as it enters into certain combinations hereinafter set forth and claimed in connection with my automatic stop mechanism.

The fabric strip first passes over a rod 28 carried by an arm 29 thence in front of a rod 30 and over a rod 31 through lateral guides 32 at opposite sides of the machine adjacent the front edge of the bench 2. While passing over the bench one edge of the fabric engages a folder 34 and is turned while the needle 5 stitches it into place. From the folder the fabric travels to the rear of the bench over a roller 35 against which it is lightly pressed by idlers 36 mounted on a vertically movable shaft 37 journaled in brackets 38.

When desired the forward end of the fabric strip is directed from the roller 35 onto the take-up or reeling roller 39 below the table, which roller is operated from the short shaft 26 by means of a crank pin 40 projecting into one end of the roller and which serves to turn the roller in order to wind the fabric upon it. This, however, is fully explained in the parent application, Serial No. 252,527, and need not be repeated.

It will be noted that the pulley 25 is provided with a second groove 42 and a belt 43 engaging this groove operates a pulley 44 to drive the roller 35 over which the fabric has previously passed. The belt 24 which operates to turn the shaft 26, when engaging the pulley 25, is adapted to be shifted to the loose pulley 41 whenever the shaft 26 is to be thrown out of operation, and this is done through a shifting lever 45 pivoted at 46 and operated through a link

47 which link is fulcrumed above to one arm of a bell crank lever 48 rocking upon pin 49, Figure 5.

To the other arm of this bell crank lever there is fulcrumed a link 50 having its other end pivoted to an arm 51 fixed on a short shaft 52, journaled in a bracket 53 at the rear of the machine frame.

A second arm 54 fixed to this shaft 52 has a connecting link 55 pivoted to a starting lever 56, which in turn is pivoted at 57 in front of the machine and provided with an operating handle 58 at its upper end. This control lever 56 is adapted to set the entire mechanism in condition for operation, as well as to start the machine, as will hereinafter be more fully explained.

When the lever is pulled forward the shaft 52 is rocked so that the arm 51 operates through the link 50 to rock the bell crank lever 48. This, in turn, pulls up on the link 47 to rock the bell crank lever 45 and shift the belt 24 from the loose pulley 41 to the clutch pulley 25, which, in turn, operates the roller 39.

If the setting lever is released by the automatic stop mechanism so that it moves back to the position shown in Figure 1, the operations are reversed, that is, the belt 24 is shifted to the loose pulley 41, thus throwing the roller 39 out of operation.

The lever 56, above referred to, operates also to throw the usual clutch 59 of the sewing machine into and out of operation by means of a cam lever 60 rocking on fulcrum 61, causing a cam 62 to press in the ordinary clutch 59, Figure 1, whereby the pulley 10 will operate the sewing machine. The other arm 63 of this cam lever is provided with a pin 64 on which a spring 65 acts to rock the cam lever 60 and thus release the clutch of the machine. The pin 64 is engaged by an arm 66 fixed to the shaft 52, which latter, as above stated, is rocked by the setting lever 56. When the shaft 52 is rocked by the forward movement of the setting lever 56, the arm 66 acts on the pin 64, thereby to move the cam lever 60 and throw in the clutch 59. Whenever the setting lever 56 is released, it is thrown back by the action of the spring 65 which also operates the cam lever 60.

Referring now more specifically to the device for stopping the machine at or about the time the end of the fabric has reached the needle, attention is particularly directed to Figure 4. A spring 67 is adapted to be coiled around the rod 31 of the gate and is provided with a spring arm 68 resting on the fabric between the rod 31 and the folder 34. This spring has its opposite end formed as an arm 69, which presses a weight 70 carried on the upper end of the arm 71. The weight is so poised that the light pressure of the arm 69 will hold it just to one side

of the fulcrum 72 of the arm 71. When the fabric ceases to hold up the spring arm 68 the pressure of the arm 69 on the weight is released and gravity causes the arm 71 to swing forwardly to the left in Figure 4. The arm 73 moves with the arm 71 and this draws upon a chain 74 to swing an arm 75 pivoted at 76 and normally held over to its full line position by the spring 77. It will be apparent that the weight 70 will exert a greater force on the arm 75 than if the spring 67 acted directly thereon, because the force becomes greater as the arm 71 moves from near the vertical towards a horizontal position. A link 78 connects at one end to the arm 75 and at the other end to a bell crank lever 79. To the other arm of this bell crank lever a link 80 is attached with its upper end connected to one arm of a lever 81 pivoted at 82. The other arm of the lever 81 is provided with a cam-shaped member 83, Figures 2 and 3, adapted to act on a roller 84 carried by the lever 85. When the arm 75 is rocked by the swinging weight 70 to the dotted line position shown in Figure 4, as it will when the fabric ceases to support the arm 68, the action is transmitted through link 80 to lever 81, Figure 5, which acts on the roller 84 and to a slide 80^a (specifically constructed and operable like the slide 80 in my copending application, Serial No. 663,490, filed September 18, 1923) to rock the lever 85 on its pivot 85^a, and thus release a latch 86 so that the setting lever 56 moves back and stops the machine through clutch 59 and belt shifter 45 associated with the winding roll 39.

The operator may stop the machine at any time, of course, by release of latch 86 permitting the setting lever 56 to swing over, otherwise the machine operates automatically until the end of the fabric approaches the machine, whereupon the latch 86 is released, and the machine will be stopped and with it the reeling device 39.

It will thus be seen that the present invention provides a simple and practical device particularly applicable to automatic sewing machines adapted to stop the same if the supply of material to be stitched should become exhausted.

Without further analysis, the foregoing will so fully reveal the gist of the invention that others can, by applying current knowledge, readily adapt it for various applications without omitting certain features that,

from the standpoint of the prior art, fairly constitute essential characteristics of the generic or specific aspects of this invention, and, therefore, such adaptations should and are intended to be comprehended within the meaning and range of equivalency of the following claims.

I claim:

1. In a machine of the class described, a movable element, means to control operation of the machine through movement of said element, means to operate said element by feed of the material up to the point of exhaustion including a material-engaging device having a spring, a weighted lever arm normally held slightly to one side of its fulcrum by light pressure of said spring, and a connection flexible longitudinally disposed between said arm and element to enable the weight of the arm to exert maximum force on said element when released by said spring to draw said connection and thereby move the element and associated parts. 70

2. In a machine of the class described, a rockable element, means to control operation of the machine through movement of said element, a spring urging said element to normally inactive position, means to operate said element by feed of the material up to the point of exhaustion including a material-engaging device having a spring, a weighted arm normally held slightly to one side of its fulcrum by light pressure of the spring, and a connection longitudinally flexible located between said arm and element to enable the weight of the arm to exert maximum force on said element when released by said first mentioned spring to draw said connection and thereby move the element and the associated parts. 95

3. In a machine of the class described, in combination, with a power-control clutch and a setting lever, a second lever, said second lever controlling said clutch, a spring urging said second lever to clutch releasing position, a connection between said setting lever and second lever whereby said spring also urges said setting lever to off position, latch means to hold said setting lever in set position, and means to automatically retract said latch means by feed of the material up to the point of exhaustion. 100

Witness my hand this 15th day of Sept., 1923.

JOHN BOSTON.
